W. W. HICKS

ELECTRIC AIR HEATER

Filed May 31, 1927

FIG. 3.

FIG. 1.

FIG. 2.

INVENTOR:
William Wesley Hicks
BY:
White, Prost & Trager
his ATTORNEYS.

UNITED STATES PATENT OFFICE.

WILLIAM WESLEY HICKS, OF SAN FRANCISCO, CALIFORNIA.

DESIGN FOR AN ELECTRIC AIR HEATER.

Application filed May 31, 1927. Serial No. 22,236. Term of patent 14 years.

To all whom it may concern:

Be it known that I, WILLIAM WESLEY HICKS, a citizen of the United States, and a resident of the city and county of San Francisco and State of California, have invented a new, original, and ornamental Design for an Electric Air Heater, of which the following is a specification, reference being had to the accompanying drawing, forming part thereof.

Referring to the drawing:—

Figure 1 is a front elevation,

Figure 2 is a side elevation, and

Figure 3 is a top plan view of an electric heater embodying my design.

I claim:

The ornamental design for an electric air heater as shown.

WILLIAM WESLEY HICKS.
